TIME SWITCH MECHANISM

George Stokes, Long Beach, Calif., assignor of
one-half to Chas. H. Adams, Long Beach,
Calif.

Application April 3, 1936, Serial No. 72,601

3 Claims. (Cl. 200—39)

This invention relates to a time controlled switch mechanism whereby a switch is opened and closed at timed intervals, said intervals being adjustable by the operator.

5 An object of my invention is to provide a time controlled switch mechanism which is simple in construction, inexpensive to manufacture, and which will effectively make and break a contact.

Another object is to provide a novel time controlled switch mechanism, the actuating dial of which rotates once in twenty-four hours, and in rotating, will open and close an electrical circuit, the opening and closing of the circuit being accomplished at a distance from the dial, thereby 10 eliminating the possibility of an electrical short circuit or arc.

20 A further object is to provide a time switch mechanism of the character stated in which the opening and closing of the contact is rapidly accomplished with a snap action thereby preventing the formation of an electrical arc.

25 Other objects, advantages and features of invention may appear from the accompanying drawing, the subjoined detailed description, and the appended claims.

In the drawing

Figure 1 is a top plan view of my time switch mechanism.

Figure 2 is a side elevation of the same.

30 Figure 3 is an enlarged side elevation of the two control arms.

Figure 4 is a side elevation of the trigger post.

Figure 5 is a plan view with the dial removed, showing the actuating fingers in cocked position.

35 Figure 6 is a view similar to Fig. 5 but with the actuating arms removed and showing one finger released and the other cocked.

Figure 7 is a view similar to Fig. 6, with both fingers released.

40 Figure 8 is a bottom plan view of one of the actuating arms.

Figure 9 is a transverse sectional view of the mounting block in which the actuating fingers slide, the fingers being shown in elevation.

45 Referring more particularly to the drawing, the numeral 1 indicates a chronometer of usual and well known construction, and which may be either electrically or spring actuated. The chronometer 1 continuously rotates a shaft 2 in one direction. The chronometer drives the shaft 2 thru suitable reduction gearing 3, the details of which form no part of this invention.

50 A disc 4 is fixedly mounted on the shaft 2 and the periphery of this disc is calibrated into hours or fractions thereof, as shown at 5. A pair of re-

leasing arms 6, 7 are mounted on the shaft 2 and rotate with this shaft. These two arms are adjustable relative to each other and about the shaft 2. This adjustment is accomplished by loosening the nut 8 which nut holds the disc 4 5 onto the shaft 2. When the nut is tightened, the disc presses down against the arms, thus holding them against movement relative to each other. By this means, the arms can be adjusted to various positions about the disc 4, thereby permitting 10 the switch to be turned on and off at different times, as will be subsequently described.

A block 9 is fixedly attached to the plate 10, said block being arranged under the disc 4. A pair of plungers 11, 12 are slidably mounted in 15 the block 9, and the inner ends of each of the arms are bent upwardly to form the pins 13, 14. Coil springs 15, 16 surround the plungers 11, 12, respectively, and urge these arms outwardly for the purpose of actuating a switch as these arms 20 are released.

The switch consists of a stationary double contact 17, a spring contact arm 18 and a second spring contact arm 19. The arm 18 is normally pressed away from the contact 17 while the arm 25 19 is normally pressed against the contact 17.

The plungers 11, 12 are provided with tips of insulating material 20, 21, respectively. The insulated tips of these plungers press against the spring arms 18, 19, respectively, for the purpose 30 of opening and closing the switch. A trigger shaft 22 extends into the block 9 and into a notch 23 in the side of the plunger 11. The shaft 22 is cut away on one side so that when the cut side is rotated toward the plunger, the plunger will 35 be free to be pressed outwardly under the urge of the spring 15. A similar trigger shaft 24 is provided for the plunger 12. Each of the shafts 22, 24 is provided with a pin 25, 26, respectively. Each of the shafts 22, 24 is provided with a coil 40 spring 27 which tends to rotate the shafts into a position to engage a plunger.

The release arm 6 is provided with a depending finger 28 which engages the finger 25 as the arm rotates past the shaft 22. Thereupon, the plunger 11 is released and the switch assumes the position shown in Fig. 6. Following this action, the arm 7—provided with its depending finger 29—engages the finger 26, thus rotating the shaft 24 to release the plunger 12. Thereupon, the switch 50 is opened, and assumes the position shown in Fig. 7. On this same arm 7, there is provided a cam lug 30 with a cam surface 31. The cam surface 31 engages the pins 13 and 14 in succession and pulls the plungers 11, 12 inwardly against the 55

tension of the springs 15, 16. Shafts 22 and 24 are constantly urged into locking position by the springs which surround these shafts.

5 The operation of my switch mechanism is as follows:

The parts are first in the position as shown in Fig. 5, i. e., the switch is open, the plungers 11, 12 are drawn inwardly into cocked position. The disc 4—as it rotates—carries the arm 6 past the shaft 22 whereupon the shaft is rotated by reason of the inter-engagement of the fingers 25, 28. The plunger 11 is thus released, is forced outwardly by the spring 15, and the switch is closed, as shown in Fig. 6. At a later interval, the arm 7 is moved past the shaft 24, the fingers 26, 29 engage, whereupon the plunger 12 is released. This plunger—upon being released—engages the spring arm 19, and the switch is opened, as shown in Fig. 7.

20 It will be noted that both on opening and closing of the switch, coil springs are utilized, thus creating a snap action, that is, a quick open and close of the switch. When the switch has been opened, each of the plungers 11, 12 is cocked by the cam 30 and during this cocking operation, the switch always remains open, as shown in Fig. 5. The previous operation is then repeated. The disc 4 makes one complete rotation each twenty-four hours.

30 Having described my invention, I claim:

1. A time switch mechanism comprising a chronometer, a shaft rotatable by the chronometer, a disc on the shaft, a pair of arms adjustably mounted on the shaft, a switch adjacent the disc, a pair of plungers extending to the switch, a spring on each of the plungers urging the same into engagement with the switch, a trigger means

engaging each of the plungers, said arms having fingers thereon engaging the trigger means whereby the plungers are released to alternately open and close the switch, and means on one of the arms engageable with the plungers whereby the plungers are drawn inwardly and the trigger means set preparatory to releasing the plungers. 5

2. A time switch mechanism comprising a chronometer, a shaft rotatable by the chronometer, a disc on the shaft, a pair of arms adjustably mounted on the shaft, a switch spaced from the disc, a pair of plungers engageable with the switch, a spring engaging each of the plungers urging same into engagement with the switch, a trigger engaging each of the plungers, a finger 15 on each of the arms adapted to engage one of the triggers whereby a plunger is released to alternately open and close the switch, and means operable by the shaft to withdraw the plungers, and set the triggers. 20

3. A time switch mechanism comprising a chronometer, a shaft rotatable by the chronometer, a disc on the shaft, a pair of arms adjustably mounted on the shaft, a switch spaced from the disc, a pair of plungers engageable with the 25 switch, a spring engaging each of the plungers urging same into engagement with the switch, a trigger engaging each of the plungers, a finger on each of the arms adapted to engage one of the triggers whereby a plunger is released to 30 alternately open and close the switch, means to cock the plungers, said means including a cam on one of the arms, a pin on each of the plungers, said cam engaging the pins as the shaft rotates thereby cocking the plungers. 35

GEORGE STOKES.
